CHECKSTRAP

John C. Crocker, Ware Shoals, S. C.

Application November 15, 1943, Serial No. 510,335

5 Claims. (Cl. 139—165)

This invention relates to an improved check strap for looms which is easily placed in position without the necessity of removing the picker stick, and which is so constructed that when replaceable parts become worn, the same can be replaced, thus providing a substantially new check strap by the replacement of worn parts.

It is an object of this invention to provide a check strap for looms having a replaceable wearing surface disposed at each end of the check strap for receiving the impact of the picker stick, which impact receiving surfaces can easily be removed and new ones replaced when the impact receiving surfaces or members become worn or damaged in any way.

It is another object of this invention to provide a check strap having means for frictionally mounting the same to resist the impact of the picker stick in both directions, and the ends of the check strap having impact receiving surfaces which can easily be renewed.

Some of the objects of the invention having been stated, other objects will appear as the description proceeds, when taken in connection with the accompanying drawings, in which:

Figure 1 is a side elevation of one end of the lay of a loom showing my check strap attached thereto;

Figure 2 is a bottom plan view, that is looking upward at the bottom of Figure 1;

Figure 3 is a top plan view of the check strap removed from the loom, and showing a slightly modified wear receiving surface at one end thereof, and showing the wear receiving surface member removed from the other end thereof;

Figure 4 is a view looking from the inside and towards the left at the left-hand portion of Figure 3;

Figure 5 is a vertical sectional view taken along the line 5—5 in Figure 4;

Figure 6 is a view of the right-hand portion of Figure 3, showing a slightly modified form of impact receiving member or bumper block;

Figure 7 is a view similar to Figure 6, but showing another modified form of bumper block.

Referring more specifically to the drawings, the numeral 10 indicates the lay of the loom having a conventional race plate 11 and a binder 12 together with a conventional picker stick 13 having a picker 14 on the upper end thereof. The lay of the loom has a longitudinally disposed slot 15 in which the picker stick is adapted to have movement. To each side of the lay of the loom, there is secured a bracket 22 having a pair of downwardly projecting legs 16 and 17 having

out-turned lips at their lower ends. The horizontal portion of the bracket 22 has a bolt 18 penetrating the same and the vertical portion of the bracket 22 has bolts 19 for securing the brackets to the side of the lay of the loom. The bolt 18 penetrates a hole in bracket 22 and a slot 20 in bracket 21 for adjusting the bracket 21 inwardly or outwardly. The bracket 21 has a downwardly depending leg 23 provided with an in-turned lip at the lower end thereof, the inturned and out-turned portions at the bottom of the legs 16, 17, and 23 serving to prevent downward movement of a check strap 25 which is adapted to be frictionally disposed in a circuitous path 15 between the legs 16, 17, and 23.

The check strap, at its end next to the edge of cloth being woven, has notches 26 and 27 in the upper inner edge thereof and notches 28 and 29 in the lower inner edge thereof which are 20 adapted to confine a replaceable wear receiving member 30 such as a strap of leather or canvas. The wear receiving member 30 is bi-furcated at each end, and the ends 31 and 32 overlap each other, and are secured together by means of a 25 rivet or brad 33.

The right-hand end of the check strap 25, which is the end most remote from the loom, has a plurality of holes 24 which are penetrated by a bolt 35, which has suitable washers 36 on 30 each end thereof, with a nut 37 on the free end of the bolt, and disposed between the free ends of the check strap 25 is a bumper or wearing block 38 which is made of a plurality of layers of leather or other suitable material, the form shown 35 in Figure 2 having the layers 39 and 40 extending outwardly which are glued to and cover the inner end of the outer laminations to provide a sloping surface to guide the picker stick into the deepest portion of the notch formed in the 40 bumper block.

In Figure 3, a slightly modified form of bumper block or wearing member is shown in which a block 45 of any suitable material is adapted to have a wear receiving surface such as a strip 45 of leather or canvas 46 secured between the inner surfaces of the lug strap and the block 45, and then being led around and following the contour of the notched end of the block to provide a wear receiving surface against which the picker stick 50 strikes when a shuttle is received into the shuttle box.

In Figure 6, a slightly modified form of the bumper block or wear receiving surface at the outer end of the check strap is shown. Here 55 a suitable block such as rubber or the like, indi-

cated by reference character 50 is shown. This has slanting shouldered portions 51 leading into a notched portion 52 into which the picker stick is adapted to fit, as the shuttle is received into the shuttle box.

It is thus seen that the notches 26 to 29 inclusive hold the replaceable wearing member 30 in position and prevent its creeping around, and holds it in a place where the picker stick will engage it as a shuttle is expelled from the shuttle box. It is also seen that a wear receiving member or bumper block is disposed at the other end of the check strap for checking the travel of the picker stick when a shuttle is received into the shuttle box. This wear receiving member or bumper block is shown in a variety of forms, but in all forms, it is easily replaceable when worn or damaged to a point beyond a serviceable condition.

In Figure 7 a substantially triangular shaped bumper block 55 is shown. This block 55 can be made of rubber, leather, or other suitable material. It is disposed between the free ends of the strap 25 and has a flat surface against which the picker stick strikes when a shuttle is received into the shuttle box. It is secured in position between the free ends of the strap 25 in the same manner as shown and described relative to Figures 3 and 6, except that wedge-shaped washers 56 are also provided.

By having the bumper block in any form, such as indicated by reference characters 45, 50, and 55 at the extreme outer ends of the lay of the loom, the guiding surfaces 39 and 40, or 46, or 51 and 52, or the ends of the strap 25 all serve to guide and center the picker stick as it is moved outwardly by an incoming shuttle, and to thus properly align the picker stick ready for it to be projected through the shuttle box toward the cloth being woven to project the shuttle to the other end of the lay of the loom.

In the drawings and specification, there has been set forth a preferred embodiment of the invention and although specific terms are employed, they are used in a generic and descriptive sense only, and not for the purpose of limitation, the scope of the invention being defined in the claims.

I claim:

1. A check strap for looms comprising a strap folded to cause its ends to be adjacent each other, a bumper block secured to and between the free ends of the strap, the inner upper and lower

edges of the strap at its folded end having notches therein and a replaceable wearing member secured around the strap, and disposed in said notches.

5. A check strap for looms comprising a strap folded to cause its ends to be adjacent each other, a bumper block secured between the free ends of the strap, the inner upper and lower edges of the strap at its folded end having notches therein and a replaceable wearing member secured around the strap, and disposed in said notches, said bumper block being composed of a plurality of layers of material extending in parallel relation to the ends of the strap, the central portion of said layers being shorter than the layers in the outer portion of the block, the layers adjacent each side of the central portion extending outwardly and covering the ends of the outer layers to provide a replaceable wearing surface.

3. A check strap for looms comprising a strap folded to cause its ends to be adjacent each other, a bumper block secured between the free ends of the strap, the inner upper and lower edges of the strap at its folded end having notches therein and a replaceable wearing member secured around the strap, and disposed in said notches, said block having a replaceable wearing member having its ends disposed in parallel relation to the inner surfaces of the strap and confined between the block and the strap and having its central portion covering the front surface of the block to provide a replaceable wearing surface.

4. A check strap for looms comprising a strap folded to cause its ends to be adjacent each other, a bumper block secured between the free ends of the strap, the inner upper and lower edges of the strap at its folded end having notches therein and a replaceable wearing member secured around the strap, and disposed in said notches, said bumper block having a substantially V-shaped notch on its inner surface adapted to receive and guide a picker stick of the loom when engaged by the picker stick.

5. A check strap for looms comprising a strap folded to cause its free ends to lie adjacent each other, a substantially triangular shaped bumper block secured between the free ends of the strap, the closed end of the strap having notches in its upper and lower inner edges and a replaceable wearing strap secured around the check strap, and having its edges fitting into said notches.

JOHN C. CROCKER.
